UNITED STATES PATENT OFFICE.

ALEXANDER J. ARTHUR, OF FORT DODGE, IOWA.

FOLDING BLIND FOR WINDOWS.

SPECIFICATION forming part of Letters Patent No. 341,542, dated May 11, 1886.

Application filed August 31, 1885. Serial No. 175,682. (No model.)

To all whom it may concern:

Be it known that I, ALEXANDER J. ARTHUR, of Fort Dodge, in the county of Webster and State of Iowa, have invented an Improvement in Folding Blinds for Windows, of which the following is a specification.

In my application No. 159,762, filed March 23, 1885, there are vertical slats connected together edge to edge by hinges, and folding back and forth so as to be closed up against the window-case, and such slats are connected up to form sections adapted to the window-frame. Usually four such sections will be made use of—two in the upper part and two in the lower part of the frame—the places of separation being central, vertical, and horizontal lines.

In my present improvements the slats are hinged together so as to fold in the same manner, and the sections are similarly placed and connected in the window-frame; but the slats themselves are constructed in the manner hereinafter described, so as to allow for the passage of light and air between the slats.

In the drawings, Figure 1 is an elevation of several slats placed together and hinged, and Fig. 2 is a section of the slats at the line *x x*, Fig. 1, in larger size.

The slats A A are hinged together at B B, so as to be folded in opposite directions or zig-zag, as in my aforesaid application, and to close back against the window case or frame. The hinges may be of any desired character, and do not form any part of this application. The slats are of suitable width and thickness, and of a length adapted to the window-frame, so that the section formed of these slats may compose one of the sections used in the window-frame. Where the hinges B are applied, the edges of the slats are square, or nearly so. Between the hinges, and preferably above and

below such hinges, the edges of the slats are beveled, as at C C, so that there are diagonal openings between the slats. These openings admit the passage of the atmosphere for ventilation and allow some light to enter, in order that the blinds may not require to be open during daylight for passage about a room; but too much light is excluded. Usually the edges of the beveled portions overlap, as shown, the slats at such beveled portions being wider than they are at the places where the hinges are applied. This prevents the rays of light passing through the joint at right angles to the plane of the blind. The edges of the slats at the inner and outer edges of the sections should be square, as at D D, and the slats may be perforated if it is desired to admit more light.

The beveled portions C improve the appearance of the blind. The slats composing the sections extend above and below the hinges. They can be cut or sawed off at either top or bottom, or both, to accommodate smaller sizes of windows, and one or more slats can be removed if the sections are too wide, or the slats can be lapped and fastened in the middle.

I claim as my invention—

1. A folding blind having vertical ranges of slats hinged together at alternate edges so as to fold together, and the slats beveled on their edges, except where the hinges are applied, substantially as set forth.

2. The slats for folding window-blind sections, having square edges for the reception of the hinges and beveled edges between the hinges, the slats being wider at the beveled edge than at the square portions, as set forth.

Signed by me this 20th day of August, 1885.

ALEX. J. ARTHUR.
